UNITED STATES PATENT OFFICE.

WILLIAM G. HARTWIG, OF CHICAGO, ILLINOIS, ASSIGNOR TO RAILWAY UTILITY COMPANY, OF CHICAGO, ILLINOIS, A CORPORATION OF ILLINOIS.

REGULATOR FOR ELECTRIC-HEATING SYSTEMS.

1,365,782.

Specification of Letters Patent. Patented Jan. 18, 1921.

Application filed March 25, 1918. Serial No. 224,435.

To all whom it may concern:

Be it known that I, WILLIAM G. HARTWIG, a citizen of the United States, residing at Chicago, in the county of Cook and 5 State of Illinois, have invented certain new and useful Improvements in Regulators for Electric-Heating Systems, of which the following is a specification.

My invention relates more particularly to 10 that form of heating system commonly employed on street railway cars or the like. It has for some time been customary to employ electric heaters for this purpose and to maintain the temperature of the car be- 15 tween certain limits by means of thermostatic control. My invention relates to the means for controlling the heating system and has for its object to provide a simpler and less expensive system which is less liable 20 to get out of operative condition, and consumes a minimum amount of current in the regulation.

In the accompanying drawings I have 25 illustrated diagrammatically a preferred embodiment of my invention. It is to be understood, however, that the specific disclosure is for the purpose of exemplification only, and that the scope of the invention is defined in the following claims in which I 30 have endeavored to distinguish it from the prior art so far as known to me, without, however, relinquishing or abandoning any portion or feature thereof.

Referring now to the drawing the source 35 of current is represented diagrammatically by line 1, the trolley for taking current to the particular car at 2 the heater 5 and the contactor for controlling the current at 3. When the contactor 3 is closed the heating 40 current travels from line 1 through the trolley 2, armature 15, contacts 3, and blowout coil 4 to the heaters 5 and thence to ground at 6 the course of the heating circuit being shown in heavy lines. The armature 15 and 45 contacts 3 are controlled by the magnet 7 of the contactor and the latter receives its current for maintaining the contacts closed when the temperature is below that desired through the following circuit-line 1, trolley 2, wire 8, the coil of magnet 7, wire 9, relay contacts 10, wire 11, resistance 12, re- 50 sistance 13, and to ground at 14. Resistance 13 is preferably of about 4000 ohms so that the current flowing through this controlling circuit is relatively very small, indeed.

The purpose of resistance 12 will presently appear.

The relay switch 10 is controlled by a magnet 16 of very fine winding and which is inserted in a shunt about the magnet 7, relay contacts 10 and resistance 12, from the trolley 2, by wire 3^a, to the coil of magnet 16, thence by wire 17 to a thermometer-thermostat 18, and when the thermostat closes the circuit by wire 19 to resistance 60 13. When the temperature is below that desired the circuit just described is open at the thermometer-thermostat which is an instrument well known in this art and need not be herein described. When, however, the 65 temperature attains the desired degree the column of mercury in the thermometer-thermostat closes the circuit and the relay coil 16 is thereby energized. This causes the magnet to attract its armature 20 which in rising trips the arm 21 of the bell crank switch member 22. As the armature 20 rises and first comes into contact with the arm 21 it closes a shunt as follows,—from coil 13 through coil 12, wire 11, arm 21, 70 armature 20 and wire 3^a. The resistance 12 is so chosen, in practice about 50 ohms has been found to work satisfactorily, that when this circuit is closed the current through the thermometer-thermostat is greatly reduced but remains of sufficient volume to cause the coil 16 to retain the armature which has previously been raised. After 75 the circuit just described has been closed the further movement of the armature 20 operating on the arm 21 opens the contacts 10 and deenergizes magnet 7, by which the heating circuit is maintained closed. Thereupon the heating circuit opens and 80 remains open until the temperature again falls below that required. When this happens the circuit is of course broken through the thermometer-thermostat, the relay coil 16 deenergized, dropping its armature, opening the circuit at the contact between 85 said armature and arm 21, closing the contact 10 and again energizing coil 7 to attract its armature 15 and close the contacts of the heating circuit. When the temperature again rises to the required point the 90 100 operation is repeated.

It will thus be seen that the circuit through the thermometer-thermostat, which is a somewhat delicate instrument and incapable of withstanding high electrical 105 110

pressures, closes the circuit through the relay, it does so with the shunt comprising armature 20 and arm 21 open but at the time the circuit through the thermometer-thermostat is broken, that instrument is shunted by the armature 20 and arm 21 so that a very feeble current is passing at the time. Thus danger of rupture of the thermometer-thermostat is avoided. It will also be observed that in my improved system the coils 7 and 16 are or may be grounded so that there is no necessity for expensive installation of the core or of the coils.

I claim:

- 15 1. In a device of the class described, a grounded electric heater, a connection from a source of electric energy to said heater, a pair of contacts interposed in and controlling said connection, an electro-magnetic device for maintaining the contacts closed including a coil connected to said source of electric energy and to ground, a relay
- 20

switch, a larger and a lesser resistance in the connections of said coil to ground, a relay coil controlling said switch and a thermostat in shunt to said lesser resistance and switch.

2. In a device of the class described, a grounded electric heater, a connection from said heater to a source of electric energy, 30 a contactor in said connection, a coil controlling said contactor, a relay switch, a connection from said relay switch to said coil, a small resistance connected to the relay switch, a larger resistance connected to the 35 first said resistance, a connection from the larger resistance to ground, a shunt about said small resistance, and a switch comprising a thermostat and a coil, an armature electrically connected to and controlled by said 40 coil and adapted when attracted thereby to engage and open said switch and also to shunt said thermostat.

WILLIAM G. HARTWIG.
